(57) **CLAIM**

The ornamental design for a tampon capsule, as shown and described.

DESCRIPTION

FIG. 1 is an isometric view of a tampon capsule; FIG. 2 is a front side view thereof; a back side view being a mirror image of front side view; FIG. 3 is a top plan view thereof; FIG. 4 is a bottom plan view thereof; FIG. 5 is an exploded view thereof showing the tampon capsule in an open position; and, FIG. 6 is another exploded view thereof showing the tampon capsule in an open position. The broken lines shown in FIG. 4 illustrate portions of the tampon capsule that form no part of the claimed design. The broken lines shown in FIG. 5 illustrate environment and form no part of the claimed design.
